FERDINAND A. F. SCHMID, OF ROSEMARY, NORTH CAROLINA, ASSIGNOR TO DRAPER CORPORATION, OF HOPEDALE, MASSACHUSETTS, A CORPORATION OF MAINE

FILLING-REPLENISHING LOOM

Application filed October 10, 1929. Serial No. 398,652.

This invention relates to looms and more particularly to looms of the filling replenishing type.

Looms of the above general character are now usually provided with a feeler mechanism for effecting replenishment of filling from time to time and also with a filling fork mechanism for stopping the loom in case the filling fails.

10 It may happen at times that the feeler mechanism will call for replenishment of filling on the same detecting beat that the filling fork mechanism calls for loom stoppage, and one of the purposes of the present 15 invention is to prevent the feeler mechanism from effecting replenishment of filling when, on the same detecting beat, the filling fork mechanism operates to effect loom stoppage.

The invention and new combination of 20 parts will best be made clear from the following description and the accompanying drawings showing one good practical form of the invention.

In the drawings:

25 Fig. 1 is a perspective view of portions of a loom provided with the present invention;

Fig. 2 is a perspective view on an enlarged scale, with some of the parts broken away, 30 showing the filling fork mechanism and portions of the feeler controlled train of mechanism for effecting replenishment of filling;

Fig. 3 is a fore-and-aft section through the breast beam showing the relation of parts 35 when the filling feeler mechanism is prevented from effecting replenishment of filling; and

Fig. 4 is a sectional detail.

The filling replenishing mechanism at the 40 side of the loom opposite the feeler mechanism is not herein shown and described in detail, because such details form no part of the present invention and are now well understood by those familiar with the art.

45 The loom frame 1 may be of usual construction and the side frames thereof are connected by the breast beam 2 upon the upper surface of which is mounted the filling fork stand 3 which supports the filling fork slide 4. The filling fork slide has mounted

upon its rear end portion at 5 the filling fork 6 adapted to engage the filling on a detecting beat when filling is laid in the shed. The filling fork 6 may be of usual construction and is provided with the loop 7, in the present instance, adapted to engage the shoulder 8 of a member 9 mounted upon the cam follower 10, the construction being such that should filling be laid by the shuttle and the lay be moved frontwardly on its detecting beat, the filling fork will be tilted, as usual, and the loom will continue to run. If, however, filling fails or is absent on a detecting beat, the filling fork will fail to be tilted, whereupon the loop 7 will be engaged by the cam follower actuated member 9 and the filling fork slide will be moved frontwardly to thereby effect loom stoppage.

Any suitable form of stopping mechanism may be associated with the filling fork slide, but as shown in the present instance of the invention, the filling fork slide 4 has extending from one side thereof the lug 11 which is engaged by one end of a knock-off lever 12 pivoted on the loom frame at 13 and having 70 its opposite end 14 resting against a shipper 15 normally held in running position in a notch 16 formed in the shipper stand 17. This form of stop mechanism is well adapted for use in connection with the filling form 75 mechanism and serves to bring the loom to rest when the filling fork detects absence of filling on a detecting beat.

Extending from the shipper stand 17 is an 80 arm 18 on which is mounted a feeler stand 19 for the support of a feeler 20. The feeler mechanism including the feeler stand, the feeler 20 and the associated parts, may be of any suitable character, the essential in this respect being that upon each detecting beat 85 the feeler will detect the condition of the filling in the shuttle and when it has reached a certain degree of exhaustion will call for a change of filling. The feeler mechanism illustrated in the present instance is, or may 90 be, of the same general type as shown and described more fully in the Brown and Re-pass Patent, No. 1,593,426, dated July 20, 1926.

The transmitter 21 extends laterally from 95

the feeler stand and is connected to a bell crank 22, one arm 23 of which is normally out of the path of a cam follower actuated member 24. The bell crank 22 is mounted for pivotal movement at 25 upon a sliding actuator 26, the construction being such that should the feeler 20 be moved longitudinally of the shuttle on a detecting beat, it will raise the arm 23 of the bell crank into the path of movement of the member 24, to thereby initiate replenishment of filling, as will be later explained.

Extending transversely of the loom is the transverse or rock shaft 27 which, as usual, is mounted in the brackets 28, one at each side of the loom. Secured to the rock shaft 27 is the upwardly extending arm 29 having a bifurcated portion 30. The front end of the sliding actuator 26 is provided with a slot 31 through which passes a pin 32, thereby connecting the sliding actuator 26 with the upper end portion of the arm 29.

From the construction thus far described it will be apparent that should the sliding actuator 26 be moved frontwardly it will slide on the pin 32 without effecting any rocking movement of the rock shaft 27 and consequently not call for replenishment of filling. Since, however, the function of the sliding actuator 26 is to effect replenishment of filling by frontward movement of the sliding actuator under normal conditions of loom operation, the present invention provides a toggle connection between the arm 29 and the actuator 26, such that the toggle is normally straightened and therefore prevents sliding movement of the actuator 26 relative to the arm 29.

One member 33 of said toggle connection is mounted on the pin 32 and pivotally connected at 34 with the companion toggle member 35, which is of the flat plate formation as shown, and which is pivotally connected to the sliding actuator 26 at 36. Thus when the toggle is straight as indicated in the normal position of parts in Figs. 1, 2, the pivotal connection at 34 of the toggle members will be below the pivotal connection 36 of the toggle member 35 with the sliding actuator, with the result that the toggle will normally remain straightened in order to transmit frontward movement of the actuator 26 to the arm 29 secured to the transverse or rock shaft 27.

It may be desirable at times to insure that the toggle will have its members in straightened or stressed transmission relation, and to this end the toggle member 33 is secured to the pin 32 by a cotter pin 37, and mounted upon the pin 32 where it extends laterally from the arm 29 is a sleeve 38 about which is wound a coiled spring 39, one end of which is secured to the sleeve at 40 and the other end to the arm 29 at 41, the result being that the tendency of the spring acting through the

sleeve 38 which is secured to the pin 32, will be to hold the toggle in straightened position, as indicated in Figs. 1 and 2. To prevent overthrow of the toggles under the action of the spring 39, the toggle member 35 has a stop 42 which overlies the sliding actuator 26 and has a horizontal portion 43 to engage the top of the sliding actuator when the toggle is straightened and the pivotal point 34 between the toggle members is slightly lower than the pivotal connection 36 between the toggle member 35 and the actuator 26, with the result that any frontward movement of the sliding actuator 26 will effect rocking movement of the transverse or rock shaft 27 and replenishment of filling.

Pivotedly connected to the toggle member 35 at 44 is the toggle trip 45 which extends rearwardly and is provided with a lug 46, and extending upwardly from the filling fork stand 3 is a fixed stop 47, the construction being such that when the lug 46 extending from the toggle trip engages the fixed stop 47 rising from the filling fork stand, the toggle connection between the sliding actuator 26 and the arm 29 will be broken and parts will take the position as indicated in Fig. 3, so that on frontward movement of the sliding actuator 26, the transverse shaft 27 will not be rocked and filling replenishment will not be called. This is the condition desired when the feeler mechanism calls for replenishment and the filling fork mechanism on the same detecting beat calls for loom stoppage, and in order to control the position of the toggle trip relative to the stop 47, the filling fork slide 4 has pivotally connected thereto at 48 a toggle trip controller 49 which has a head portion 50 provided with an incline 51 adapted to contact with a similar incline 52 formed on the toggle trip. Under normal condition of parts as indicated in Figs. 1 and 2, the incline 51 of the trip controller 49 is rearward of the fixed stop 47, with the result that the incline 52 on the toggle trip, and 51 on the trip controller, will serve to lift the toggle trip to carry the lug 46 above the stop 47 when the feeler calls for replenishment of filling and the filling fork mechanism is not actuated to call for loom stoppage. When, however, the filling fork mechanism calls for loom stoppage due to absence of filling laid in the shed, the filling fork slide 4 will be moved frontwardly, thereby carrying the trip controller 49 frontwardly and permitting the lug 46 on the toggle trip to remain in position to engage the fixed stop 47 as the sliding actuator 26 is moved frontwardly by the cam follower. Under these conditions the toggle trip will be prevented from moving frontwardly with the sliding actuator 26, and owing to its pivotal connection with the toggle member 35 will trip the toggle from the position of Fig. 2 into that of Fig. 3, so that the toggle will

not transmit frontward movement of the actuator 26 to the arm 29, and the actuator 26 will move idly frontward by reason of the pin and slot connection with the arm 29.

5 Under normal weaving conditions when filling is laid in the shed, the feeler mechanism will act as usual to effect replenishment of filling from time to time, so, also, the filling fork mechanism will act to effect loom stoppage when filling fails to be laid in the shed while there yet remains a working supply of filling in the shuttle. If, however, the feeler calls for replenishment of filling from any cause and the filling fork mechanism calls 10 for loom stoppage by reason of failure of filling, on the same detecting beat, the feeler mechanism will be prevented from effecting replenishment of filling and the loom will stop under the dictates of the filling fork mechanism.

20 In the present illustration of the invention, the transverse shaft 27 has loosely mounted thereon the hub 54 of an arm 55 which serves as a convenient pivotal connection, as at 48, for the trip controller 49 which, of course, is movable towards and from the front of the loom with the filling fork slide.

What is claimed is:

1. In a filling replenishing loom, the combination of a filling feeler to detect the condition of the filling in the shuttle, a train of mechanism under control of the feeler to effect replenishment of filling when the feeler detects substantial exhaustion thereof, a filling fork mechanism to detect the presence or absence of filling in the shed, means actuated by the fork mechanism to stop the loom when the filling fork mechanism detects absence of filling, and a trip for rendering said train of mechanism inoperative to prevent the filling feeler from effecting replenishment of filling when it detects substantial exhaustion of filling and the fork mechanism detects absence of filling on the same detecting beat.

2. In a filling replenishing loom, the combination of a filling feeler mechanism to effect replenishment of filling when the filling is substantially exhausted in the shuttle, a filling fork mechanism to stop the loom when filling fails, and a feeler mechanism trip for throwing the feeler mechanism out of action for preventing the feeler mechanism from effecting replenishment of filling when it detects substantial exhaustion of filling in the shuttle and the filling fork mechanism detects failure of filling on the same detecting beat.

3. In a filling replenishing loom, the combination of a filling feeler mechanism to effect replenishment of filling, a filling fork mechanism to stop the loom when filling fails to be laid in the shed, and a trip device for rendering the filling feeler mechanism ineffectual to replenish the filling in the

shuttle when both the filling feeler mechanism and the filling fork mechanism detect faults in the filling on the same detecting beat that the loom may be stopped without changing the filling in the shuttle.

4. In a filling replenishing loom, the combination of a filling feeler to feel for the filling in the shuttle on detecting beats, mechanism under control of the feeler to effect replenishment of filling including a toggle, a filling fork mechanism to effect loom stoppage on failure of filling, and means rendered effective to trip the toggle and prevent replenishment of filling when both the filling feeler and filling fork mechanisms detect faults in the filling on the same detecting beat that the loom may be stopped without replenishing the filling.

5. In a filling replenishing loom, the combination of a filling feeler, a train of mechanism to initiate replenishment of filling under control of the feeler, a filling fork slide having a filling fork mounted thereon, loom stopping means actuated by frontward movement of the filling fork slide, and a device made operative by frontward movement of the filling fork slide for rendering said train of mechanism inoperative to replenish the filling when the feeler calls for a change of filling and the filling fork slide is moved frontwardly on the same detecting beat due to failure of filling.

6. In a filling replenishing loom, the combination of a filling feeler, a train of mechanism to initiate replenishment of filling under control of the feeler including a toggle, filling fork mechanism including a filling fork and filling fork slide, means actuated by frontward movement of the filling fork slide for stopping the loom, and means rendered effective to trip the toggle and thus cause the train of mechanism to become inoperative to replenish the filling when the feeler calls for a change of filling and the filling fork slide is moved frontwardly on the same detecting beat.

7. In a filling replenishing loom, the combination of a filling feeler, a train of mechanism under control of the feeler to effect replenishment of filling including a normally straightened toggle, a toggle trip, a filling fork mechanism to effect loom stoppage on failure of filling, and means for rendering the toggle trip operative to trip the toggle when, on the same detecting beat, the feeler calls for a change of filling and the filling fork mechanism calls for loom stoppage.

8. In a filling replenishing loom, the combination of a filling feeler, a train of mechanism to initiate replenishment of filling under control of the feeler including a toggle, a spring normally acting to hold the toggle in operative position, filling fork mechanism including a filling fork and filling fork slide, means actuated by frontward movement of

the filling fork slide for stopping the loom, and means rendered effective to trip the toggle and thus cause the train of mechanism to become inoperative to replenish the filling 5 when the feeler calls for a change of filling and the filling fork slide is moved frontwardly on the same detecting beat.

9. In a filling replenishing loom, the combination of a filling feeler, a train of mechanism under control of the feeler to effect 10 replenishment of filling and including a toggle to transmit stress through said train of mechanism to replenish the filling, a toggle trip, a filling fork and filling fork slide to 15 stop the loom on failure of filling, means for causing the toggle trip to become operative to trip the toggle should the feeler call for a change of filling on the same detecting beat that the filling fork calls for loom stoppage.

10. In a filling replenishing loom, the combination of a filling feeler, a train of mechanism under control of the feeler to effect 20 replenishment of filling and including a break-connection in said train, a break-connection trip, a filling fork to stop the loom 25 on failure of filling, and means for causing the trip to become operative to trip the break connection should the feeler call for a change of filling on the same detecting beat that the 30 filling fork calls for loom stoppage.

11. In a filling replenishing loom, the combination of a filling feeler, a train of mechanism under control of the feeler to effect 35 replenishment of filling and including a break joint connection normally held in power transmitting position, a filling fork and slide to effect loom stoppage when filling is absent, and means rendered operative by frontward movement of the filling fork slide for moving 40 the break joint connection into non-power transmitting position when the feeler calls for replenishment of filling and the filling fork detects a fault in the filling on the same detecting beat that filling replenishment may 45 be prevented and the loom be stopped.

In testimony whereof, I have signed my name to this specification.

FERDINAND A. F. SCHMID.
